Attorney

UNITED STATES PATENT OFFICE.

ELMER U. AMES, OF COLLINGSWOOD, NEW JERSEY.

KNITTING MACHINE.

Application filed May 31, 1924. Serial No. 717,184.

My said invention relates to knitting machines and particularly to controlling means for the individual needles whereby the capacity for variation in operation of the machine is increased without interfering with other operations of the machine.

It is an object of the invention to provide means for controlling the individual needles with precision and certainty which means shall be simple and not liable to get out of order.

Referring to the accompanying drawings, which are made a part hereof and on which similar reference characters indicate similar parts,

Fig. 1 is a partial vertical section of a knitting machine,

Figure 2, a plan view of a detail of the construction,

Figure 3, a vertical section of another modification, and

Figure 4, a plan view of a detail of Figure 3.

In the drawings reference character 10 indicates the frame of the machine on which is mounted a stationary needle cylinder 11 having slots for needles 12 which may be of any conventional or desirable type and are held in place by spring rings 13 as usual. The slots of the needle cylinder adjacent their lower ends are made deeper so as to accommodate, jacks 14 which in this instance are shown as having upright arms lying in the slots behind the lower or butt ends of the needles. Each jack also has a horizontal arm extending approximately perpendicular to the upright arm. The jacks are held in place on the needle cylinder by a spring ring 14' in a manner substantially similar to the needles whereby they may have rocking movement in the needle slots.

In the present embodiment of the invention a cam ring 15 is shown as surrounding the cylinder. A ring 16 revolves with the cam ring, this ring having an inclined cam surface at 17 for engaging under a shoulder at the upper end of a jack actuator in the form of a rod 18 so as to lift the rod which is held up by the elevated portion of the ring 16 during the greater part of the rotation of the machine and is only lowered at such a time as the needle cams approach the particular rod and the needle and jack controlled thereby.

Each rod 18 in addition to the shoulder coacting with the cam 17 has a shoulder at

the opposite side for engaging the horizontal arm of a corresponding jack, the heads of the rods and the horizontal arms of the jacks being preferably guided between projections 19 on a ring 20 on the base 10' which form a comb for guiding all the jacks and the rods 18. At its lower end each rod is connected to a rockarm 21 forming one arm of a lever pivoted at 22 said arm being guided between projections of a comb 23. A spring 24 is secured at one end to a fixed abutment 25 and at the other to an upwardly extending arm 26 rigid with the arm 21 said arm 26 forming the other arm of the lever referred to. The two arms forming the lever may be loosely journaled on a pivot at 22 or may be otherwise supported for pivotal movement on the frame of the knitting machine.

Each lever has a downward projection 27 adapted to enter openings 28 in a roller 29 unless prevented by a band 30 preferably made of paper which passes over the roller and which has perforations adapted to register with the openings 28. By reason of this construction it will be seen that as the cam ring revolves the rods 18 are held up during the greater part of each rotation by means of ring 16 but are lowered at each rotation to permit lugs 27 to engage with the band 30 or to pass through the same if a perforation in the band happens to be opposite the opening 28 which is then uppermost. If desired a row of openings or a slot may extend longitudinally of the roller 29. When a lug passes into such an opening in the roller the lever will fall so far as to permit the head of the rod to drag down the horizontal arm of the corresponding jack and thus move the vertical arm outward so as to move the butt of the needle into the path of the needle-cams on the ring, which cams are more specifically illustrated and described in my copending application Serial No. 717,182 of even date herewith. The roller carrying the paper band is indexed at each rotation of the cam ring, such operation being permitted by the lifting of the rods 18 which, as has been stated, are held up during the major part of a rotation of the cam ring.

In the modified form shown in Figures 3 and 4 frame 10'', a cylinder 11'', and a cam ring 12'', all as in Figures 1 and 2. The needle cylinder supports jacks which have uprights arms and other arms extending at an angle to the body which angle, however, is less than that in Figure 1. At the lower ends

of the inclined arms of jacks 33 there are a series of elements 34, one for each jack having slots receiving the lower ends of the jacks, said elements being slidably supported in 5 combs on a frame member 35 for which reason they will hereinafter be referred to as slides though they could obviously be supported for pivotal and lengthwise movement in other ways than that here shown. A ring 36 is secured to the frame and has projections 37 forming a comb for guiding the outer ends of the members 34. A ring 38 is secured to and revolves with the cam ring 12". The ring 38 has inclined cam faces at 39 and 40 10 on which the members 34 travel up and down and also has cam faces 41 and 41'. Each of the members 34 has secured thereto a rod 42 which is connected by any conventional or desirable means to pattern mechanism preferably of approximately similar character to that shown in Figure 1. The members 34 are, in effect, heads similar to the heads of rods 18, but are pivotally connected to rods 42.

In the operation of the device last described 25 the cam ring revolves about the stationary needle cylinder and the needles are out of engagement with the needle operating cams as in Figure 1 except when they are flexed by the jacks so as to bring the needle butts into the 30 path of the cams. It should be noted in this connection that the needles at their upper ends remain in the needle slots so as to prevent entry of lint and dust. The members 34 are maintained in elevated position at their 35 rear ends as illustrated in dotted lines in Figure 3 by means of the horizontal elevated part of the ring 38 and when in this position the jacks are idle. As the members 34 approach the position illustrated in Figure 5 they ride down the incline 40 so far as 40 permitted by the pattern mechanism and if they are permitted to ride all the way down said incline, the ends of the jacks come into the path of the incline 41 whereby the members 45 are advanced along radial lines so as to rock the jacks and throw their upper ends forward thereby moving the butts of the needles into the paths of the needle-cams. After the members 34 pass the high part of their 50 projecting cam they next ride down the incline 41' and then up the incline 39 where they are again held in idle position during the remainder of the rotation of the cam ring.

The band 30 is driven by the roller 29 or 55 other convenient means which is indexed, i. e. turned step-by-step, by a ratchet or the like acting directly on the roller 29 or on some part acting in timed relation therewith. It will be understood that this indexing mechanism acts during the time that the rods 18 or corresponding parts are held up by the horizontal part of their operating cam, whether this extends approximately all the way around the cam ring or only a fraction 60 thereof, as in machines with a plurality of

feeds. When the rods 18 are lowered the springs 24 will force the lugs 27 into the openings 28, such action being somewhat assisted by gravity.

Various efforts have been made to utilize 70 jacquard mechanism in connection with knitting machines having independent needles. In some cases the wheel or other rotary element supporting the card or band of the jacquard has had a revolving motion and also 75 a movement at right-angles to its axis of rotation, the wheel moving bodily toward the ends of the needles or jacks so as to push up such needles or jacks as did not have corresponding holes in the belt or card. Such 80 mechanisms are very destructive to the jacquard belt or card. In my arrangement the card or belt only selects the jacks and needles and the cams do the work of raising the needles so that if a needle works hard it 85 will not damage the paper as the tension of the spring 24 is the greatest pressure that ever comes on the paper.

As above stated the devices illustrated may 90 be used in machines of various types and in various ways. The necessary modifications for such purposes will be obvious to those skilled in the art and therefore I do not limit myself to what is shown in the drawings and described in the specification but only as indicated in the appended claims. I do not limit myself to the use of jacquard mechanism per 95 se for controlling the jacks and through them the needles of my machine, but may use pattern mechanism of other types where such 100 use seems desirable.

Having thus fully described my said invention, what I claim as new and desire to secure by Letters Patent is:

1. In a knitting machine, a base, a stationary slotted needle cylinder on said base, normally-idle needles in the slots of the cylinder, rocking jacks having angularly related arms one of which lies back of a needle, rods extending up through the needle bed each 110 rod having shoulders one of which is positioned to engage an arm of a jack to rock the jack and thereby bring its needle into range of a needle cam, a pattern form serving to control selectively the engagement of said 115 shoulders and said arms, and a cam moving in timed relation with the needle cams said cam engaging another shoulder on each of said rods for normally preventing engagement of said first-named shoulders and said 120 arms.

2. In a knitting machine, a base, a stationary slotted needle cylinder on said base, normally-idle needles in the slots of the cylinder, rocking jacks having angularly related arms 125 one of which lies back of a needle, rods extending up through the needle bed each rod having shoulders one of which is positioned to engage an arm of a jack to rock the jack and thereby bring its needle into range of a 130

- needle cam, a pattern form at one side of the needle cylinder said form movable about a horizontal axis, a series of levers pivoted respectively to individual rods said levers ful-
 5 crumed at the side of said form remote from said needle cylinder and having lugs to enter holes in the form, resilient means for moving said levers to cause said lugs to engage open-
 10 ings in said form, a cam moving in timed relation with the needle cams said cam engaging another shoulder on each of said rods for nor-
 mally preventing engagement between said first-named shoulders and the arms operated thereby.
 15 3. In a knitting machine, a needle bed, needle cams, a normally-idle needle slidable in said bed, a jack having an arm behind the needle and an arm projecting therefrom, a cam movable with the needle cams, a T-
 20 shaped rod having a shoulder for engaging the jack to rock the same and move the needle toward a needle cam and another shoulder for engaging said cam to be normally sup-
 25 ported thereby out of operative relation to said jack, a band having pattern openings therein, and a lever pivoted to said rod said lever having a lug adapted to enter an opening in the band when said rod is lowered by said rod-supporting cam.
 30 4. In a circular knitting machine, a sta-
 tionary slotted needle cylinder, a series of normally-idle independent needles therein, rotary needle cams, a series of elbow-shaped
 35 rocking jacks each having one arm lying in a needle slot back of the shank of the needle in said needle slot and another arm extending radially of the cylinder, a set of rods each having a shoulder positioned to engage the radial arm of a jack for rocking the same
 40 to bring the corresponding needle into reach of a needle cam, a cam rotating with the needle cams said cam engaging another shoulder on each rod during a part of a rotation to prevent engagement of the first-named
 45 shoulder with its jack, a perforated pattern band, a set of levers each connected to a rod of said set, a lug on each lever shaped to pass through perforations in said pattern band, and resilient means acting to move the levers
 50 in a direction for engaging the lugs with the pattern band and the first-named shoulders with the corresponding jacks.
 5. In a knitting machine, a needle cylinder and a cam ring having relative rotation, a set of needles in the slots of the cylinder, a set of rocking jacks having arms lying behind the needle shanks and mechanism operating on the jacks selectively to control the position of the needles relatively to the cams said mechanism including a traveling perforated pattern, a series of levers each pivoted at a point remote from the needle cylinder and each having an arm extending over said pattern toward said cylinder, lugs on said arms for entering perforations in said pattern, means acting on the arms nearest the cylinder for normally holding said lugs away from the pattern, and individual springs acting on the other arm of each lever in opposition to said means.
 6. In a knitting machine, a needle bed, a needle cam, a normally-idle needle slidable in said bed, a rocking jack having an arm behind the needle and an arm projecting therefrom, a cam movable with the needle cam, a rod having a head for engaging the project-
 70 ing arm of the jack to rock the same and move the needle toward the needle cam, a band having pattern openings therein, a lever pivoted to said rod said lever having a lug adapted to enter an opening in the band, said head also being positioned to be engaged by said second-mentioned cam for elevating said lug above said band.
 7. In a knitting machine, a needle bed, a needle cam, a jack, a cam movable with the needle cam, a rod having a head for engaging the jack to move the needle toward operating relation with the needle cam, a band having pattern openings, a lever pivotally connected to said rod said lever having a lug to enter an opening in the band, said head also being positioned to be engaged by said second men-
 80 tioned cam for holding said lug away from said band.
 In witness whereof, I have hereunto set my hand at Philadelphia, Pennsylvania, this 15th day of May, A. D. nineteen hundred and twenty-four.

ELMER U. AMES.
